[57] **CLAIM**

The ornamental design for a saddle bag cooler, as
shown and described.

DESCRIPTION

FIG. 1 is a perspective view of a saddle bag cooler
showing my new design;

FIG. 2 is a top plan view thereof;

FIG. 3 is a bottom plan view thereof;

FIG. 4 is an end elevational view thereof, opposite to
that shown in FIG. 1;

FIG. 5 is a front elevational view thereof;

FIG. 6 is a rear elevational view thereof;

FIG. 7 is a developed top plan view thereof;

FIG. 8 is a perspective view of a saddle bag cooler
showing a second embodiment of my new design, the
only differences being in the reduced depth of the two
compartments and the absence of a zipper closure for
the inner top cover of the compartments; and

FIG. 9 is a perspective view of a saddle bag cooler
showing a third embodiment of my new design, the
only differences being in the enlarged width of the two
compartments and the arrangement of the zipper clo-
sure on the inner top cover of the compartments.
